Inventor

Josiah Rosecrans,

United States Patent Office.

JOSIAH ROSECRANS, OF BERKSHIRE, OHIO, ASSIGNOR TO ADELIA R. SWARTZ, OF CARLISLE, PENNSYLVANIA.

Letters Patent No. 101,920, dated April 12, 1870.

IMPROVED LIFTING-JACK.

The Schedule referred to in these Letters Patent and making part of the same.

To all whom it may concern:

Be it known that I, JOSIAH ROSECRANS, of Berkshire, Deleware county, of the State of Ohio, have invented a new and useful Improvement on Lifting-Jacks; and I do declare that the following is a full, clear, and exact description of the same, reference being had to the accompanying drawing making a part of this specification, corresponding parts being indicated by the same letters.

The drawing represents a longitudinal elevation of the machine. It may be cast of malleable iron.

A-X is the lever employed in lifting, the power being applied at A; the weight is at X.

a is the fulcrum;

C is the stem; and

D E is the base or foot upon which it rests.

The stem C consists of two upright bars, connected by rivets or pins, as a g h i f.

Between these bars on a and f, revolves the lever A X, and the base D E. When the short arm of the lever X is put under any weight, to the lifting of which the lifting-jack is adapted, as, the axle of a vehicle, and the long arm A depressed, the weight, in being sufficiently elevated, is transferred to the top of the stem C at B, where it rests, even when the power at A is withdrawn.

The arms of the base D E are of unequal length, so as to give the stem C different degrees of elevation, adapting it to different heights of the weight to

be lifted. When the arms of the base are horizontal or at right angles with the stem C, then the stem has the lowest of three different elevations. When the short arm E is made the base, as represented by the dotted lines E D, then a higher elevation is attained. When the longer arm D is made the base, then the greatest length of C is attained, as is represented by the dotted lines D E. The arms of the base form an angle with each other at the pin f, so as to secure a firmer position when their ends are employed as the base. The pins h and i are intended to prevent the arms from passing too far from a perpendicular position, endangering the stability of the support.

Having thus described my invention, so that any one skilled in the art can make and use it, I make the following

Claim.

I claim as my invention and desire to secure by Letters Patent—

The adjustable base, for lengthening the jack C, which is provided with the lever A by means of the unequal arms of the base D and E, substantially as herein shown and described.

JOSIAH ROSECRANS.
